DESIGN.

C. B. SMITH.

FABRIC.

No. 18,348.

Patented May 22, 1888.

UNITED STATES PATENT OFFICE.

CHARLES B. SMITH, OF FITCHBURG, MASSACHUSETTS.

DESIGN FOR FABRIC.

SPECIFICATION forming part of Design No. 18,348, dated May 22, 1888.

Application filed April 13, 1888. Serial No. 270,598. Term of patent 3½ years.

To all whom it may concern:

Be it known that I, CHARLES B. SMITH, residing at Fitchburg, in the county of Worcester and State of Massachusetts, have invented and produced a new and original Design for Fabric, of which the following is a full, clear, and exact specification.

My new design is fully illustrated in the accompanying photograph, to which reference is made.

A A are wide parallel composite stripes, alternated by the narrower plain stripes B B. The stripes A are each composed of the two stripes a a, the two narrower stripes b b between the stripes a a, and the central narrow stripe or line, c, between the stripes b b. The

stripe a shows clusters of dots a', the stripes b b show parallel lines b', and the central stripe, c, shows irregular spots or spirals c'. The stripes B are made up of transverse lines of dots e, as clearly shown in the photograph.

I claim—

The design for fabric herein shown and described, the same consisting of wide parallel composite stripes A and alternate plain stripes B, the stripes A showing the two narrow stripes a a, the two stripes b b between the stripes a, and the central stripe, c.

CHARLES B. SMITH.
